HOLLOW-POINT BULLET.

1,101,743.

Specification of Letters Patent. Patented June 30, 1914.

Application filed February 24, 1914. Serial No. 820,617.

To all whom it may concern:

Be it known that I, FRANK O. HOAGLAND, a citizen of the United States, residing at Bridgeport, county of Fairfield, State of Connecticut, have invented an Improvement in Hollow-Point Bullets, (Case A,) of which the following is a specification.

This invention relates to the class of bullets broadly designated as hollow point bullets, the forward end of which will mushroom, *i. e.* flatten or spread out, upon impact with an objective, and the invention has for its object to provide a bullet of this type which shall be relatively inexpensive to produce and exceedingly effective in use, owing to its superior mushrooming quality, and shall moreover be admirably adapted for use as an illuminating bullet.

With these and other objects in view I have devised the novel bullet which I will now describe, referring to the accompanying drawing forming a part of this specification and using reference characters to indicate the several parts.

Figure 1 is a sectional view showing the slug from which my novel bullet is formed, and also the action of the first die thereon; Fig. 2 a plan view of the slug corresponding with Fig. 1, and showing the die in horizontal section; Fig. 3 a view partly in elevation and partly in section showing the bullet during the process of formation, after the action of the first and second dies, and before the action of the third die; Fig. 4 an elevation of the partly formed bullet as seen from the left in Fig. 3; Fig. 5 an elevation of the completed bullet; Fig. 6 an elevation of a modified form of slug, and Fig. 7 is a plan view corresponding therewith.

10 denotes one form of slug from which my novel bullet may be formed, the essential features of which are a cup-shaped recess 11 in its forward end surrounded by a wall 12. The exact configuration of the recess or the 15 height of the wall are not essential features of the invention. I preferably however, as shown in the drawing, form the outer side of the wall of the slug parallel with the axis thereof and form the wall of diminishing 20 thickness from the base of the recess outward. The bullet is completed by swaging tools, indicated by 13, the action of which is to split the wall into four sections and to cause said sections to close the tip of the 25 bullet and to overlap, as indicated in Fig. 3.

It makes no difference so far as the principle of the invention is concerned just how the swaging tools are arranged to operate. It is thought sufficient for the purposes of this specification to state that the action of the first tool, which may be single or double acting, is to shear out two opposite sections from the wall of the tip, to fold one section, as 14, over inward, and to fold the second section, indicated by 15, over inward upon it, then another tool or a member of a double acting tool folds the third section, indicated by 16, over inward upon section 15, after which another tool or a member of a double acting tool folds the fourth section indicated by 17, inward over upon section 16. In Fig. 3, the first and second sections, indicated by 14 and 15 respectively, are shown as folded to place, the third section, indicated by 16, is ready to be folded to place 75 by the next action, after which the fourth section, which faces section 16 but is cut away in the drawing, is folded to place, leaving the sections superposed. It is not considered necessary to illustrate in detail 80 the operation of these swaging tools, as their action will be obvious to anyone skilled in the art. The folding or closing over of the four sections leaves a closed central recess 18 in the forward end of the bullet, which may 85 be made larger or smaller, as may be required, by lengthening or thickening (either or both) the wall surrounding recess 11 in the slug. The swaging together of the sections makes the closed central recess water 90 and grease proof.

The bullet comprising this invention is admirably adapted to use as an illuminating bullet. No change is required in the process of manufacture, but a mass of a suitable 95 flashing compound, indicated by 20, that will produce a flame or a puff of smoke or both when ignited by impact, is placed in the recess 11 in the slug and the sections of the wall closed over it in the manner already 100 described.

The form illustrated in Figs. 6 and 7 differs in that the wall of the slug as formed comprises a plurality of sections, indicated by 19, the edges of which are convex curves. 105 These sections may be folded over successively or simultaneously as they do not overlap. The edges are swaged tightly together and close the central recess as effectually as in the other form, making it water and 110

grease proof and protecting a compound in the recess, if used.

Having thus described my invention I claim:

5. A bullet of the character described formed from a slug having a cup-shaped recess in its forward end, the wall of the recess forming the tapering portion of the completed

bullet and being closed inward in the form of superposed overlapping sections.

In testimony whereof I affix my signature in presence of two witnesses.

FRANK O. HOAGLAND.
